UNITED STATES PATENT OFFICE.

WILLIAM H. HARTMAN, OF LOS ANGELES, CALIFORNIA, ASSIGNOR TO RANDALL CONTROL AND HYDROMETRIC CORPORATION, OF LOS ANGELES, CALIFORNIA, A CORPORATION OF CALIFORNIA.

ELEVATOR-DOOR-LOCKING SYSTEM.

Application filed November 24, 1920. Serial No. 426,210.

To all whom it may concern:

Be it known that I, WILLIAM H. HARTMAN, a citizen of the United States, and a resident of Los Angeles, county of Los Angeles, State of California, have invented certain new and useful Improvements in Elevator-Door-Locking Systems, of which the following is a specification.

The invention relates to elevator door operating devices and particularly to means for locking the door against opening movement.

Most elevators are provided with shaft doors having locks which function to lock the door against opening movement when the door is fully closed. Many elevator doors are provided with motors operated by air under pressure, for opening and closing the doors. It frequently occurs that the air motor does not operate to fully close the door, so that the lock does not operate, permitting the door to be subsequently opened without operating the lock. This is a source of constant danger, since it permits a person in the hall-way of a building to move the door open, with the resultant liability of serious injury.

An object of my invention is to provide means for locking the door against opening movement when it is wholly or partially closed, so that if it is only partially closed it cannot then be opened by a person in the hall-way.

A further object of the invention is to provide an elevator door locking system as above set forth, which may be released to permit the door to be moved open, only when the elevator car is brought to rest at the door.

The invention possesses other advantageous features, some of which, with the foregoing, will be set forth at length in the following description where I shall outline in full that form of the invention which I have selected for illustration in the drawings accompanying and forming part of the present specification. In said drawings, I have shown two embodiments of my invention, but it is to be understood that I do not limit myself to such forms, since the invention, as set forth in the claims, may be embodied in a plurality of other forms.

Referring to the drawings:

Figure 1 is an elevation of an elevator

door operating system embodying my invention.

Figure 2 is an elevation of a fragment of the system shown in Fig. 1.

Fig. 3 is an elevation of the fragment shown in Fig. 2 parts thereof being broken away.

Fig. 4 is a plan view of the parts shown in Fig. 2.

Fig. 5 is an elevation of a modified form of system.

Fig. 6 is an elevation of a fragment of the system shown in Fig. 5, parts thereof being broken away.

The door opening and closing mechanism may be mounted on the wall of the elevator hatchway, one motor being provided for each door, or the mechanism may be mounted on the elevator car, so that one motor serves to operate all of the doors in the hatchway, as shown in my co-pending application Serial Number 409,758, filed in the U. S. Patent Office on Sept. 13, 1920. In the present application, I have shown the mechanism mounted on the wall of the hatchway. The particular door moving mechanism shown forms no part of the present invention and any suitable form of apparatus may be employed for that purpose. In the arrangement shown in Fig. 1 I have employed a fluid operated motor having two cylinders 2-3 in which are disposed pistons connected by the rod 4. Admission of air under pressure into cylinder 2 moves the rod to the right and admission of air into cylinder 3 moves the rod to the left.

The admission of air into the respective cylinders is controlled by the valve 5, which is connected to the source of air supply and to the cylinders and which is also provided with an exhaust port, so that when air is flowing into one cylinder it is exhausting from the other. The valve lever is connected by a rod 6 to a lever 7, which is connected by the rod 8 to a lever 9. The lever 9 is provided with a pin or projection 12 on one

end which is adapted to be engaged by a cam or shoe carried by the elevator car, the cam or shoe being movable so that it contacts with the pin 12 as the elevator reaches the floor at which it is desired to open the door. The cam rocks the lever 9, thereby operating the valve 5 to open the door. The release of the car by the operator moves

the valve to shut the door. The door is moved by the lever 13, fulcrumed at its upper end to the hatchway and connected at its lower end to the door 14. Intermediate 5 its ends, the lever is connected by the link 15 to the cross head 16, secured to the piston rod 4.

Means are provided for locking the door against opening movement from a plurality 10 of positions, including the fully closed position, and one or more partly open positions. Arranged on the rear face of the cross head 16 is a stop 17 which is engaged by teeth 18 on the latch 19, pivoted to the stationary 15 cross bar 21. The latch 19 is provided with a plurality of spaced teeth 18 and the successive teeth drop behind the stop 17 as the door approaches the closed position and prevent opening movement of the door by persons other than the elevator operator. The 20 teeth are arranged so that when the stop is in engagement with the first tooth the door is partly open; when it is in engagement with the second tooth, the door is open a lesser amount and when it is in engagement 25 with the third tooth, the door is fully closed.

Means are provided for raising the latch to release the door when it is desired to open it. Mounted on the lever 7 is a roller 30 22 engaging a cam surface or eccentric surface 23 on the under side of the latch, so that when the lever 7 is moved to operate the door opening means, the latch is raised to move the teeth out of the path of the stop. 35 The cam surface 23 is so shaped that when the lever 7 is rocked in the opposite direction to operate the door closing means the latch is lowered so that its teeth lie in the path of the stop. Should the door fail to 40 fully close, for some reason, the latch will prevent it from being moved open from its partly closed position.

In Figs. 5 and 6, I have shown a modified form of construction in which a single cylinder air motor 25 is used to open and close 45 the door. In this construction, the air control valve 27 is operated by the rod 28 connected to the lever 29, which is equivalent in function and mode of operation to the lever 50 9 in the former construction. The piston in the cylinder is connected to the cross head 31 which is connected to the door as heretofore described. The cross head is provided on its upper surface with a plurality of 55 spaced teeth 32 which are engaged by the latch 33 as the door approaches closed position, so that the door is held locked in the closed position and in one or more partially

closed positions. When it is desired to open the door, the latch is raised by the sliding 60 cam 34 connected to the lever of the control valve by the rods 35 and 36 and the lever 37. The principal difference between the two constructions shown is that in the first construction the latch is provided with a plurality of teeth for engagement with a stop, whereas in the second construction the latch has a single tooth arranged for engagement with a plurality of stops. 65

I claim:

1. In combination, an elevator shaft door, means for moving the door, means for locking the door in a plurality of positions against an opening movement, and means for simultaneously controlling the door moving means and for operating the locking means. 70

2. In combination, an elevator shaft door, means for moving the door toward its open position, means for controlling the moving means, means for locking the door in a plurality of positions, and means for insuring that the locking means is operative except when the control for the door moving means is operated to move the door toward its open 80 position. 85

3. The combination with an elevator shaft door, of means for moving the door toward closed position, of a latch arranged to engage the door moving means to lock the door against opening movement in a plurality of positions. 90

4. The combination with an elevator door, of means for moving the door and a latch engaging the door moving means for locking the door against opening movement in a plurality of positions. 95

5. The combination with an elevator door, of a fluid operated motor, a cross head on said motor connected to said door and a latch engaging said cross head and adapted to hold it at a plurality of positions against opening movement of the door. 100

6. The combination with an elevator door, of a fluid operated motor, a valve for controlling the operation of said motor, a cross head on said motor connected to said door, a latch adapted to engage said cross head and adapted to hold it at a plurality of positions against opening movement of the door and means for concurrently operating said valve and latch. 105 110

In testimony whereof, I have hereunto set my hand.

WILLIAM H. HARTMAN.
